UNITED STATES PATENT OFFICE.

WALLACE E. C. STONE, OF LOS ANGELES, CALIFORNIA.

GAS LOCK.

Application filed August 24, 1923. Serial No. 659,157.

To all whom it may concern:

Be it known that I, WALLACE E. C. STONE, a citizen of the United States, residing at Los Angeles, in the county of Los Angeles 5 and State of California, have invented new and useful Improvements in Gas Locks, of which the following is a specification.

My present invention being termed a "gas lock", it will be understood that this invention is intended to be used in the control of the flow of gasoline from a tank, such as the vacuum tank commonly used on automobiles, to an explosion engine, or the like; but it should also be understood that the 15 device herein described and claimed is suitable to be employed wherever it is necessary to take precautions against unauthorized use or withdrawal of fluids delivered through pipes.

20 My present invention may be described as an interposable unit, adapted to be inserted in a pipe line and comprising a connecting head and a control extension; and, in a preferred embodiment, the mentioned 25 connecting head may be provided with an inlet opening at or near the top thereof and with a plurality of outlet openings so spaced apart as to permit of the selection of a preferred outlet opening to be connected with an outlet or delivery pipe, there being a 30 valved interior opening between the mentioned inlet and outlet openings.

It is a primary object of this invention to 35 provide novel and effective means for controlling an interior valve between inlet and outlet openings of a gas lock; and my preferred means for this purpose may comprise a valve whose stem projects into a control extension, which extension may house a 40 spring tending to seat the said valve and also a milled head, or the like, provided with threaded engaging means permitting of a manual adjustment, and optionally permitting also of a manipulation by means of a 45 suitable key,—even when the said milled head, or its equivalent, shall be rendered comparatively inaccessible by the interposition of a suitable lock, which may be removably secured within said extension.

50 Other objects and advantages will appear from the following description of one

preferred embodiment and an alternative embodiment of my invention, and from the appended claims, as illustrated in the accompanying drawings, wherein:

55

Fig. 1 is a vertical section showing my gas lock permanently connected with a vacuum tank.

Fig. 2 is a horizontal section on the line 2—2 of Fig. 1.

60

Fig. 3 is a vertical section similar to Fig. 1, but showing an alternative construction of valve operating means.

Referring to the details of that specific embodiment of my invention which I have chosen for purposes of illustration, my gas lock may be regarded as comprising a connecting head 1, integral with a control extension 2, the said head being provided with a threaded inlet opening 3, at or near the top thereof, and with one or more outlet openings 4, 4', shown as arranged in substantially the same horizontal plane and extending substantially at right angles to the mentioned inlet opening. By providing a plurality of outlet openings 4, 4', I am enabled conveniently to bring one or another of the mentioned openings, only two being shown in the form of my device which I have selected for illustration, into a position favorable for the connecting of an outlet pipe, such as the outlet pipe 5, provided with a coupling 6, having a threaded connection with the nipple 7, screwed into the outlet opening 4, the unused opening 4' being closed in any suitable way, as by means of a threaded plug 8.

Any suitable means may be employed to connect the inlet opening 3 with a source of fluid supply such as a gasoline tank or the vacuum tank 9, but I prefer to employ for this purpose threaded connections such as the bushing 10, and the nipple 11, the latter being shown as secured to an outlet fitting 12, at the bottom of the vacuum tank 9, and to the bushing 10, by means preventing the removal of my gas lock, such as transverse pins 13, 14, a similar pin 15 being also optionally employed to prevent the removal of the bushing 10 from the inlet opening 3.

In the form of my invention chosen for

purposes of illustration, the inlet opening 3 and the mentioned outlet openings are shown as separated by a web or partition 16, provided with an opening 17, in which is seated a valve 18, whose stem 19 is shown as extending through the opening 17 and into the control extension 2, in such manner as to render the mentioned valve substantially self-seating, although permitting of a suitable control by means of any desired mechanism protected or confined within said housing or extension 2.

In order to assure an effective seating of the valve 18 when no flow of liquid is desired, I may employ resilient means such as spiral spring 20, confined within a tubular portion of the mentioned control extension and pressing against a collar or other suitable stop 21, secured on the valve stem 18; and, when a flow of gasoline, or the like, is desired, such a flow may be effected by means such as the milled head 22, having a threaded engagement, at 23, with the interior of a bushing 24, threaded or otherwise secured in the extension 2 and adapted to engage at 25 the lower end of the valve stem 19, the described construction being such as to leave the valve 18 free to find its own seat, when the milled head shall be rotated in one direction, although tending to open the valve to a predetermined degree, whenever the milled head is rotated in an opposite direction.

In order to render the milled head 22, or its equivalent, accessible only to an authorized person, I may provide the extension 2 with a skirt 26, defining a chamber 27, within which I may removably secure a lock 28, which may resemble the operating part of a trunk lock of known construction, being preferably circular in horizontal outline and provided with a pair of beveled latching elements 29, adapted to engage an inner annular ring or shoulder 30, the described construction being such that, the lock being held stationary within the skirt or housing 26, a rotation of the key 31 will cause a retraction of the latching elements 29 and permit a bodily removal of the lock 28, thereby giving access to the milled head 22, or its equivalent, by which the flow of gasoline, or the like, may be controlled from below.

Optionally, instead of employing a short key 31, I may provide the milled head 22, or its equivalent, with a nick, or the like, in the lower face thereof, in order to permit the upper end of a key, extending entirely through the lock 28, to engage and rotate said milled head, or its equivalent, this alternative construction being such that, when the lock 22 is permitted to rotate freely with the key 31', instead of being held against rotation in the manner referred to,

the key 31' may be employed directly to control the valve 18, as suggested in Fig. 3.

For the purpose of emphasizing the fact that the invention to be protected herein is by no means limited to the details of construction already described, I have suggested in Fig. 3 an alternative construction in which the milled head 22^a is provided at 32 with a threaded connection with the valve stem 19^a, in such manner that the rotation of the milled head 22^a must cause a simultaneous rotation and advance or retraction of the valve 18^a relative to its seat; and it should be understood that when either of the described constructions, or any similar construction, is employed, usual precautions must be taken against leakage, the employment of a washer 33, shown as seated against the upper face of the milled head 22^a, being suggested for this purpose, it being understood that when the valve 18 or the valve 18^a is suitably elevated to permit a free flow of gasoline, this washer will effectively contact with the lower surface of the washer 24 or 24^a.

Although I have herein described one complete embodiment and one alternative embodiment of my invention, both of these being in the form of interposable units adapted to replace an ordinary elbow, it will be understood that various features thereof might be independently employed and also that various modifications might be made therein without departure from the spirit and scope of the invention as the same is indicated above and in the following claims; and it will also be understood that my gas lock may be employed in various relationships and positions other than those to which specific reference has been made.

What I claim is:

1. A gas lock comprising a connecting head provided with an interior opening and a valve seated therein, a key controlled means for unseating said valve, the stem of said valve extending into a control extension containing a hand operating means provided with means permitting its rotation by a key, a spring tending to move the valve toward its seat and adjustable means to vary the movement of said valve stem.

2. A gas lock comprising a gasoline supply chamber having an outlet port, a conduit connecting with said port, a valve controlling said port and having a stem passing transversely through said conduit, a spring tending to move said valve toward its seat, a manually operable screw having a socket in which the end of said valve stem is positioned to move the valve from its seat, a housing below said screw and a lock in said housing preventing access to said screw.

3. A gas lock comprising a gasoline sup-

ply chamber having an outlet port, a conduit connecting with said port, a valve controlling said port and having a stem passing transversely through said conduit, a spring tending to move said valve toward its seat, an adjustable bushing, a manually operable screw in said bushing and having a socket in which the end of said valve stem is positioned to move the valve from its seat, a housing below said screw and a lock in said housing preventing access to said screw.

In testimony whereof I have signed my name to this specification.

WALLACE E. C. STONE.
